Primary Examiner — Michael A Maharajh*(74) Attorney, Agent, or Firm* — Joseph M. Jong(57) **CLAIM**

The ornamental design for a foam roller, as shown and described.

DESCRIPTION

FIG. 1 is a front elevation view of a foam roller showing my new design. The rear elevation view, bottom plan view, and top plan view are identical to the front elevation view.

FIG. 2 is a right side elevation view thereof. The left side elevation view is identical to the right side elevation view. FIG. 3 is a front elevation view thereof, with an indication of a cross section line H-H.

FIG. 4 shows a cross sectional view along line H-H in FIG. 3.

FIG. 5 is a front elevation view thereof, with an indication of a cross section line G-G.

FIG. 6 shows a cross sectional view along line G-G in FIG. 5; and,

FIG. 7 is a perspective view thereof.

The broken lines shown in the figures are for the purposes of illustrating portions of the foam roller which form no part of the claimed design.
